MAGNETIC COMPASS COMPENSATING DEVICE

Application filed July 9, 1928, Serial No. 291,393, and in France July 12, 1927.

With certain devices at present in use for magnetic compasses, variation of the compensating effect is obtained by varying the vertical distance of the compensating irons or magnets with respect to the card; suppression is possible only by a rather remote displacement or even by removal of the compensators. Said devices are cumbersome, cannot be adjusted to zero and necessitate removable and interchangeable irons or magnets.

Other semi-circular compensating arrangements contemplate the possibility of opposing the magnets; annulling is then possible but requires a great number of magnets and its maintenance is dependent on the stability of magnetization of the correctors.

The object of the invention is to provide compensating devices in which the suppression mentioned above is obtained by a particular positioning of each of the irons or compensating magnets, such positioning being geometrically determined and independent of the value of the magnetization of the correctors and not necessarily dependent upon opposite arrangements of pairs of the latter; adjustment of the correctors being effected by appropriate devices operating in a manner to dispose or position the irons or magnets at one side or the other and in one or more planes, stationary and parallel to the plane of the compass card.

In the accompanying drawings and in the description which is to follow, there are set forth different embodiments of the invention and, in the drawings:

Figure 1 is a diagrammatic view of a compensating device embodying the invention and of a semi-circular type;

Figs. 2 and 3 are diagrammatic views illustrating the elementary arrangement of two magnets whereby the relative arrangements that are to be made by their symmetric adjustment in unison with each other will afford a very accurate suppression of the compensating couple in all azimuths;

Figs. 4 to 7 are plan views illustrating several possible arrangements or groupings of the correctors;

Figs. 8 and 9 are plan views partly in sec-

tion illustrating other embodiments of the invention;

Figs. 1, 2 and 3 illustrate, diagrammatically, an embodiment of the invention which may be termed the semicircular compensation type, and this embodiment will now be described.

If, in a plane parallel to the compass card a small magnet 1 is located, calculation and experiment will show that whatever the point of the plane where the middle of said small magnet 1 is positioned, said magnet can be set in such a way that the horizontal torque exerted on the mobile gear 2 will be nil.

On each radius issuing from center O I mark the non action point A corresponding to an angle α of the magnet 1 with respect to the radius concerned. All points in the plane corresponding to angle α are on a curve C_α . If the value of α is suitably selected, said curve will very substantially be a circle c having R as a radius and concentric with the card.

If the magnet is secured on a support connected with the binnacle in the position thus defined, the compensating torque will be substantially nil for any azimuth. So, in the case of a card having one magnet 2α in length and of a single small compensator magnet:

$$\alpha = O, R = O, 7a$$

In point of fact, an arrangement so simple does not permit of an absolutely nil effect being ensured for any azimuth. But, instead of having a single magnet, I may provide a plurality of magnets in suitably arranged groups, the position of each of said magnets, defined by angle α and radius R, being fitted to the general configuration of the whole compensating device and, of course, to the design of the mobile gear.

Figures 2 and 3 show elementary arrangements of two magnets 1, each of which arrangements may be determined by means of their symmetry and combined with one another so as to afford a very accurate annulling of the compensating torque in any azimuth.

Adjustment as to direction and as to intensity of said torque is obtained by moving

the whole or part of the elements of the corrector assemblage in one or more fixed planes parallel to the plane of the card relative to the positions of non-action above defined.

5 The compensator torque thus obtained is a function very perceptibly semi-circular of the azimuth and is the closer to it the more the selected arrangement gives, in its zero position, an accurate annuling of the torque in 10 any azimuth.

Adjustment as to direction is determined by utilizing, in the well known manner, two sets connected with the binnacle and having respectively their maximum effect in two rectangular directions which are generally the one parallel to the axis of the airship and the other perpendicular to said axis. Action is exerted on the operative intensities of these 15 two sets so as to achieve a compensator resultant adjustable both as to magnitude and as to direction.

From the foregoing it is evidently possible to replace each element by a nest of magnets, arranged parallel or not, and so associated as 20 to permit of their power being varied or 25 conservation of said power ensured.

In Figures 4 to 7 inclusive, the magnets 1 are mounted on supports 2 so arranged as to be 30 slidable along slides 3. Supports 2 are controlled by means of a screw 4 provided with a knurled plug 5 and longitudinally blocked by bearings 6 integral with plate 7. In said Figures 4 and 7, the screw 4 is a right and left hand one so that the motions 35 of the two groups of magnets will be symmetrical.

With the arrangements illustrated by Figures 5 and 6 there is but one movable group and the screw is single threaded. For symmetry, there could be adjoined to those arrangements a stationary group similar to the movable group and located in a position symmetrical with respect to the latter's zero position. In all cases, the stationary supports 40 and the slides are fixedly mounted on the binnacle 7.

Figs. 4 to 7 illustrate several possible arrangements or groupings of the correctors relating solely to one of the components of the distributor field. Figs. 4 and 7 illustrate an arrangement whereby, by the use of an adjusting screw with right- and left-hand threads, the units or parts of the assemblage of magnetic correctors may be adjusted simultaneously and equally, while the arrangements shown in Figs. 5 and 6 illustrate forms in which adjustment of only one unit is required to be made.

The quadrantal compensation device is 60 best shown in Fig. 8 and is based on the employment of soft irons 11' of suitable mass and shape, positioned in a plane parallel to the card and the operative intensity of which is adjustable through adjusting their spacing 65 E parallel to axis Z-Z' without removing

them from their plane. Suppression of the quadrantal corrector effect is obtained through juxtaposition of said irons. The half-ring shape is particularly convenient since the two juxtaposed irons then 70 form a substantially complete symmetrical ring which, obviously, can have no action on the card in any azimuth. In order to further increase said symmetry, there can be provided between the two half-rings two 75 stationary air-gaps e^1 , e^2 perpendicular to the variable air-gaps E and intended magnetically to balance them in zero position.

As stated above, the invention contemplates giving to the soft iron bodies a suitable form, so that when they are adjusted with respect to each other in a direction at right angles to the axis of the compass, in a common plane above the card of the compass, they constitute an assemblage without action 80 on the same. Thus, while the compensation for quadrantal deviation may be feeble, it may be made without the necessity of separating the soft iron bodies very far from each other or removing them, while all the time preserving the possibility of compensating for a substantial deviation. The extent of adjustment is regulated by varying the separation of the iron bodies by a double movement in a plane perpendicular to the 85 axis of the compass, while the direction adjustment is effected by turning the assemblage about the axis of the compass by means of a suitable device.

The characteristic form given the two soft iron bodies is that of semi-circular rings, and when the two bodies are placed in juxtaposition they constitute a symmetrical assemblage which is obviously without action on the card at all azimuths. Also, instead of giving to the semi-annular bodies a true semi-circular form, they may be given a form approximating a square or an octagon if there be need for octantal correction.

The invention also contemplates another type of compensation, namely the octantal which is obtained by giving to the half-rings a shape approximating a square or an octagon so as to obtain, if need be, an octantal correction as distinguished from the quadrantal correction above described.

In both cases, adjustment as to intensity is effected by varying the size of the air-gaps E, and adjustment as to direction is effected by causing the set to be revolved round the axis of the card by means of a suitable device.

Such an arrangement may be embodied as illustrated, for example in Figure 9.

In this embodiment, iron bodies 17, mounted on supports 12, are slidable along a slide 13 and are controlled by a screw 14 with right- and left-hand threads. The set is mounted on a plate 8 rotatable round the axis of the compass, as, for example, by means 120

of a screw 9 tangential with respect to and meshing with a circular rack integral with plate 8.

It is to be clearly understood that the above described embodiments are not intended as in any way limitative and may be modified in any desirable manner without departing from the scope of my invention.

Having now particularly ascertained and 10 described the nature of my said invention as well as the manner in which the same is to be performed, I declare that what I claim is:

15 1. A magnetic compass compensating device, comprising, in combination with the card of the compass, means for effecting suppression of the usual compensating effect, such means comprising compensating iron bodies of substantially semi-annular form mounted at opposite sides of the axis of the 20 compass, and means operable to adjust said bodies around said compass axis in a plane parallel to the card of the compass.

25 2. A magnetic compass compensating device, comprising, in combination with the card of the compass, means for effecting suppression of the usual compensating effect, such means comprising compensating iron bodies of substantially semi-annular form mounted at opposite sides of the axis of the 30 compass, and means operable to adjust said bodies around said compass axis in a plane parallel to the card of the compass; the inner sides of the iron bodies being semi-circular and the outer sides being of angular 35 form to provide for polygonal compensation.

In testimony whereof I affix my signature.
GEORGES LOUIS JULES MARTIN.
